(57) **CLAIM**

The ornamental design for a disk with a corrugated edge, as shown and described.

DESCRIPTION

FIG. 1 is a top perspective view for a disk with a corrugated edge showing my new design;

FIG. 2 is a bottom perspective view thereof;

FIG. 3 is a front view thereof;

FIG. 4 is a top plan view thereof;

FIG. 5 is a back side view thereof;

FIG. 6 is a bottom plan view thereof;

FIG. 7 is a left side view thereof;

FIG. 8 is a right edge side view thereof;

FIG. 9 is a top perspective view thereof, shown in use;

FIG. 10 is a top perspective view thereof, shown in use; and,

FIG. 11 is a top perspective view thereof, shown in use.

The broken lines in FIGS. 9-11 depict environmental subject matter only and form no part of the claimed design.
